CAR CONSTRUCTION

Application filed May 3, 1928. Serial No. 274,707.

This invention relates to improvements in car construction, and more particularly car door sealing constructions.

In railway car construction, much difficulty has heretofore been experienced in providing and maintaining an efficient weather seal between the rear edges of the side doors and the car side walls. The clearances left between the side wall structures and the seal-forming elements carried by the rear edges of the doors when the latter are opened and shut, are often very small, as a result of which the amount to which the seal-forming elements carried by the doors may project inwardly of the plane of the doors, is necessarily quite limited and hence the size and strength of the parts carried by the door are in turn limited. Particularly is this true in the case of many double sheathed cars. It is well known that the rear edges of car doors are subject to severe usage, it being a common occurrence for pry bars, sledges and other instruments to be used in forcing the doors open and closed, with consequent danger of injuring and deforming the rear edge portion of the doors and the sealing elements and thereby destroying the effectiveness of the sealing arrangement. In addition to the foregoing, are unavoidable variations in the manufacture and assembling of the parts; changes occurring in the relation of the doors to the superstructures because of weaving of the car bodies, sagging of the door tracks and the like, all of which tends to destroy in whole or in part, the efficacy of any sealing arrangement, and more particularly, any sealing arrangement depending upon a single line of sealing contact between two elements for its effectiveness.

One object of the present invention is to provide a weather and spark seal construction for slideable car doors, which has incorporated therein a plurality of lines of sealing contact so arranged that foreign matter cannot enter the car door opening without successively passing the several seal joints.

Another object of the invention is to provide a car door rear edge and sealing arrangement wherein are employed a plurality of distinct sealed joints so that, in event of

failure or partial failure of any one of said joints, from any cause, the remaining seal joints will still be effective to prevent admission of foreign matter to the interior of the car.

A specific object of the invention is to provide an arrangement of the type above indicated wherein three lines of sealed contact are provided between the sealing elements and so arranged as to provide a plurality of air channels and thus insure carrying off by air currents, any foreign matter that may enter either of the air channels.

Other objects of the invention, such as reduced cost of manufacture, installation and maintenance; ease of replacement of parts; and increased strength imparted to the door, and generally increased efficiency will be apparent from the following description and claims.

In the drawing forming a part of this specification, Fig. 1 is broken horizontal sectional view, taken through the rear edge portion of a steel door and adjacent portions of a single sheathed car and showing the invention. Fig. 2 is a view similar to Fig. 1, but illustrating a somewhat different arrangement of door post. Fig. 3 is an enlarged broken horizontal sectional view illustrating a modification of the sealing arrangement which may be used under certain car conditions. And Fig. 4 is an enlarged sectional view of the sealing arrangement proper, illustrated in Fig. 1.

Referring first to the construction illustrated in Figs. 1 and 4, the single wood sheathing of the house car side is indicated at 10, the rear door post of the usual side door opening at 11, and one of the diagonal braces of the side wall at 12, said brace being in the form of a Z-bar, as most commonly used. The invention is illustrated in connection with a steel or all-metal door indicated generally by the reference character 13.

The particular door chosen for illustration has the main portion thereof comprised of sheet metal panels 14, the door having a vertically extending corrugation 15 adjacent its rear edge and, outwardly thereof, formed with a flat margin comprised of two plies of

55

100

sheet metal, one of which is constituted by the main panel sheets and the other by a bridging strip 16 for the vertical corrugation. The rear edge of the door is reinforced and strengthened by a buffer angle 17 and a sealing plate 18. The angle 17 has one flange 19 thereof applied over the flat marginal edge of the door and secured thereto by a series of rivets 20, said rivets 20 also securing the base flange 21 of the sealing plate 18 to the inner side of the flat marginal edge of the door.

The other flange 22 of the buffer angle 17 is extended transversely inwardly of the plane of the door and preferably abuts the rear edge of the flat marginal portion of the door and the rear edge of the base flange 21 of the sealing plate 18 so that, when blows are delivered to the buffer angle 17, as by striking the stop 23, the rivets 20 are placed under double shear, thereby increasing the effectiveness of the reinforced rear edge of the door.

The door post 11 is of a form commonly used and has a main web 24 extending perpendicularly outwardly from the wall of the car and an outer flange 25 projecting rearwardly. Secured to the post 11 is a sealing member 26 of angular cross section and having a base flange 27 secured to the web 24 of the post, as by the series of rivets 28. The member 26 is provided also with an elongated, preferably thinner flange 29 also extending rearwardly and the free edge of which may be bent inwardly as indicated at 30 to provide a cam surface when initially engaged by the inner edge of the flange 22 of the angle 17 carried by the door. Said flange 29 is preferably of limited flexibility, for the purpose hereinafter described.

The sealing plate 18 is inwardly offset at 31 and is then formed with a forwardly and inwardly inclined flange 32 adapted to enter the space between the post flange 25 and the sealing member 26.

With the construction described, it is evident that three distinct lines of sealing contact are provided between the parts when the door is in closed position. The first line of sealing contact is that between the inner edge of the flange 22 and the resilient flange 29. The second is that between the free edge of the flange 32 and the adjacent portion of the sealing member 26 and between these two lines of sealing contact will be formed a vertically extending air pocket 33. The third line of sealing contact is that between the free edge of the post flange 29 and the sealing plate 18 and it will be observed that a second vertically extending air pocket, as indicated at 34, is formed by the parts between the two said lines of sealing contact.

As will be clear from the drawing, taken in connection with the preceding description, should any snow, rain, dust or sparks be

able to pass by the first line of sealing contact, it is evident that the same will enter the air channel 33, through which there will always be a vertical current of air when the car is in motion, and hence such foreign matter will, in most instances, be removed at this point. Should this not occur, however, the foreign matter must then next pass the second line of sealing contact in which event the foreign matter enters the second air channel 34, where it is subject to the same draft action and will be removed. In practice, it is extremely difficult to maintain a line of sealing contact continuously, due to unavoidable irregularities of manufacture, indentations that may occur at intervals along the sealing elements, and from other causes, but, with the invention disclosed, while a small amount of foreign matter may possibly pass by the first line of sealing contact, at some point therein, the possibility of foreign matter passing beyond the second line of sealing contact is even less and practically impossible of passing the third line of sealing contact.

Referring to the construction illustrated in Fig. 2, a different form of door post is indicated at 124, the same being constituted by a Z-bar with a wood filler 40. In the construction illustrated in Fig. 2, which is typical of many cars now in service, it will be observed that the plane of the outer face of the post 124 is very much closer to the outer vertical plane of the braces 112 of the car side wall and hence the actual amount of clearance between the members on the rear edge of the door is extremely small.

In this modification, the door 113, buffer angle 117 and sealing plate 118 carried by the door, are the same as in the first described modification and it will be observed that both the members 117 and 118 will still clear the side wall braces. 105

On account of the limited space available for the sealing member attached to the post, a different form is employed in the Fig. 2 construction, the same being indicated generally by the reference character 126. Said member 126 is of more or less U-formation, having an elongated, rearwardly extended flange 129 corresponding to the flange 29, a shorter rearwardly extending outer flange 125 corresponding to the flange 25 of the post in the first described construction, and an intermediate web or base 41, which is secured to the post 124 by the rivets 128. By constructing the member 126 of U-section, as described, the same may be accommodated between the outer planes of the braces and door post 124, and it will be evident from the drawing, the same three distinct lines of sealing contacts and air channels are obtained in the construction of Fig. 2 as in the case of the first described form.

Referring to the modification of *Phragmites*, the arrangement of *silica* in the post 130

211, door 213, post flange 225 and sealing plate 218 carried by the door, is the same as in the construction illustrated in Fig. 1.

The construction of Fig. 3 differs primarily from that of Fig. 1 in the buffer angle 217 carried by the door, which is provided with a longer inwardly extending flange 222, so as to obtain a greater section modulus at the rear edge of the door. This can be accomplished in the car construction illustrated, because of the available clearness which is apparent from inspection of Fig. 1, without fouling of the buffer angle with the car side braces. The sealing member 226 is of generally angular cross section, having a base flange 227 secured to the post 211 by a series of rivets 228, the base flange in this instance projecting outwardly instead of inwardly, in order to avoid the diagonal brace of the car side. The member 226 is provided also with a rearwardly elongated flange 229, in this instance, terminating in an O. G. curve section 230 which cooperates with the inner edge of the flange 222, as clearly shown in the drawing. In this construction, the free edge of the sealing plate 218 forms a sealing joint with the base flange 227 of the sealing member 226. It will be evident that the three lines of sealing contact and the two air channels are present in the construction of Fig. 3, with the same advantages as hereinbefore described.

Although the preferred manner of carrying out the invention has been described, all changes and modifications are contemplated that come within the scope of the appended claims.

We claim:

1. In door construction, the combination with a member having a door opening in a wall thereof and a slidable door to close said opening; of a reinforcing element carried by the rear edge of the door and including a flange projecting transversely inwardly of the plane of the door; a sealing element carried by said member and having a resilient flange projecting rearwardly and engageable with the inner edge of said first named flange to provide a sealing joint; and additional means carried by said member and door providing another sealing joint within the first named sealing joint.

2. In car door construction, the combination with a rear door post provided with a plurality of spaced rearwardly projecting sealing elements; of a slidable door; and a plurality of inwardly extended sealing elements carried by the rear edge of the door and cooperable with the first named sealing elements when the door is in closed position.

3. In car door construction, the combination with a rear door post provided with a pair of rearwardly projecting sealing elements, said elements being laterally spaced; of a slidable door; and a pair of sealing ele-

ments carried by the rear edge of the door and projecting inwardly thereof and longitudinally spaced and cooperable with the first named sealing elements.

4. In car door construction, the combination with a rear door post provided with an outer rearwardly projecting flange section and an inner longer resilient rearwardly projecting flange section; of a door; a member carried by the rear edge of said door and having an inwardly projecting flange section cooperable with said elongated flange section; and a second member carried by the rear edge of the door cooperable with said first named flange section. 70

5. In car door construction, the combination with a rear door post having laterally offset, rearwardly projecting flange sections, the inner of which is resilient; of a slidable door, the later having a sealing plate and a buffer angle secured to the rear edge thereof, the buffer angle having one of its flanges projecting inwardly and cooperable with said resilient flange, the sealing plate cooperating with the other flange section. 80

6. In car door construction, the combination with a rear door post having an outer integral rearwardly extended flange; of a sealing member of angular cross section secured to said post, one of the flanges of said member extending rearwardly and inwardly spaced from said first named flange; and a slidable door having a buffer angle and a sealing plate secured to the rear edge thereof, said buffer angle having one of its flanges extended inwardly and engageable with the said flange of the sealing member, said sealing plate having an inwardly and forwardly inclined flange section cooperable with said post flange and an adjacent part of said first named sealing member. 90

7. In a door construction, the combination with a member having a door opening in a wall thereof and a slidable door to close said opening; of cooperable sealing elements carried by said member and the rear portion of door on the inner side thereof, respectively; a reinforcing guard member on the rear portion of the door having a section secured to the outer face thereof and a flange projecting inwardly across the rear edge of the door to protect said sealing element carried by the door; and a second sealing element on said member cooperable with the inner edge of said flange to provide an additional line of sealing contact therewith. 110

8. In a door construction, the combination with a member having a door opening in a wall thereof and a slidable door to close said opening; of a pair of spaced sealing elements 125 on said member; and a pair of spaced cooperable sealing elements on said door, one of the latter engaging one element on said member and the other element of said door engaging both of said elements on said mem- 130

ber, the three lines of sealing engagement thus formed being separated from each other and providing therebetween two separate and independent air pockets.

- 5 9. In a door construction, the combination with a member having a door opening in a wall thereof and a slidable door to close said opening; of a combined reinforcing and sealing element on the rear edge of the door
10 having a flange projecting inwardly of the plane of the door; and a cooperable sealing element on said member having a resilient flange extending rearwardly to a point beyond the rear edge of the door and said combined sealing and reinforcing element thereon, when the door is in closed position, said resilient flange engaging the inner edge of the first named flange and said resilient flange having a cam surface along its free edge.
15 10. In witness that we claim the foregoing, we have hereunto subscribed our names this 23rd day of April, A. D. 1928.

20 KENNETH J. TOBIN.
